UNITED STATES PATENT OFFICE.

HENRY A. WAGNER, OF TOLEDO, OHIO, ASSIGNOR TO THE WILLYS-OVERLAND COMPANY, OF TOLEDO, OHIO, A CORPORATION OF OHIO.

SPRING-SEAT CONSTRUCTION.

Application filed June 24, 1922. Serial No. 570,644.

This invention relates to the construction of a spring seat such, for example, as is used in automotive vehicles wherein a framework and a series of coil springs carry suitable padding and an upholstery covering. In the construction of such seats difficulty has been experienced in preventing deformation of the framework particularly the upper border wire directly supporting the padding and upholstery due to the hard or severe usage which a motor car is frequently called upon to withstand.

An object of this invention is to so brace the framework of such a seat that it shall effectively resist deformation and maintain at all times its original form and shape without any material loss in resiliency.

Another object of this invention is to so connect or secure the bracing members that they will not become detached and injure the upholstery.

Other objects and objects relating to details of construction and economies of manufacture will appear as I proceed with the description of that embodiment of the invention which, for the purposes of the present application, I have illustrated in the accompanying drawing, in which:

Figure I is a top plan view of the frame and springs of a spring seat back, the padding and upholstery being removed.

Fig. II is a cross sectional view of the same on the line II-II of Fig. I, and

Fig. III is a fragmentary view corresponding to Fig. I showing the lower halves of two springs and the manner of connecting them with a brace wire.

Similar reference characters refer to the same parts throughout the views and the sectional view is taken looking in the direction of the small arrows at the ends of the section line.

Referring now to the drawings, a base frame 5 is shown constructed of a pair of longitudinal metal strips 6 and 7 and a series of transverse metal strips 8 secured thereto at their points of intersection by means of tongues 9 struck up from the longitudinal strips and bent over the adjacent edges of the transverse strips. A lower border wire 10 extends about the periphery of the base frame and is secured to the longitudinal and transverse strips by rolling the ends of these strips over the wire. Upon this base frame is carried a plurality of coil

springs 12, preferably of the usual hour-glass shape, whose base portions are secured to the base frame by means of tongues 13 struck up from the strips forming the base frame. These springs are suitably tied together at their opposite ends by tie wires 14 and extending about the group of springs adjacent those ends is a frame comprising a top border wire 15 to which the outer springs of the group are secured by means of metal clips 16.

Extending from the top border wire 15 on that side of the seat back which is uppermost when the seat is in position are three brace wires 18 secured to the border wire 15 by clips 19 and extending diagonally downward to the longitudinal strip 7 of the base frame to which they are attached by metal clips 20. These brace wires perform an important function in maintaining the border wire 15 in proper form and preventing it from bowing inwardly when the cushion is compressed. To maintain the opposite side of the top border wire in proper form it would be desirable to employ similar means, that is, to connect that side of the top border wire in a similar manner with a portion of the base frame. However, such an arrangement has been found to be unsatisfactory for the reason that where both sets of brace wires are anchored to the base frame some of the brace wires invariably become detached at one end or the other, due to the excessive strains imposed upon them and eventually poke through the padding and upholstery covering of the seat.

To avoid this trouble brace wires 22 connected at one end with the top border wire by means of the clips 23 at the opposite end of the seat, have their opposite ends connected with portions of certain of the coil springs 12, as shown particularly in Fig. II. Connection is made to these springs by means of an anchoring wire 25 extending in a direction longitudinally of the seat and parallel with the base frame, which wire is shown in Figure I, secured to six of the coil springs near their lower portions. Since the springs are of the hour glass type, the manner of attaching the anchoring wire 25 to them will be more apparent upon an inspection of Fig. III, as in that view the upper portions of the springs are removed. As shown in that figure the anchoring wire 25 is secured to one of the lower convolutions of

each spring by means of clips 26. To this anchoring wire 25 the brace wires 22 are attached by clips 27.

From the above description and the drawing the operation of this spring seat will be readily apparent. Whenever the springs are compressed as when pressure is applied to the seat back, the brace wires 18 serve to counteract the inward pull of the springs upon the border wire, and thus maintain that portion of the border frame in proper form. The brace wires 22 function in similar manner respecting the opposite side of the top border frame, but by reason of their being connected to the anchoring wire 25 which may yield due to its connection with the springs, the brace wires 22 are relieved of undue strain which might cause them to buckle and the attaching clips thereof are saved from being torn loose.

The resiliency of the seat as so constructed is, however, not materially affected since the braces offer no resistance to the compression of the springs.

While I have shown and described in considerable detail a specific embodiment of my invention it is to be understood that this showing and description is illustrative only and for the purpose of rendering my invention more clear and that I do not regard the invention as limited to the details of construction illustrated or described, nor any of them except in so far as I have included such limitations within the terms of the following claims in which it is my intention to claim all novelty inherent in my invention broadly as well as specifically.

What I claim as new and desire to secure by Letters Patent is:

1. In a spring seat, the combination of a base frame, a top frame, a plurality of coil

springs therebetween, a pair of oppositely inclined braces between said frames, one of which forms a direct connection between the same and the other being connected to the top frame and terminating short of the base frame, and means connecting the latter brace with the springs intermediate their ends.

2. In a spring seat, the combination of a base frame, a top frame, a plurality of springs therebetween, a brace extending diagonally downward from one side of said top frame connected to said base frame intermediate its ends, a second brace extending diagonally downward from the opposite side of said top frame and means for anchoring the lower end of said second brace to one of said springs.

3. In a spring seat, the combination of a base frame, a top frame, a plurality of coil springs connected at opposite ends to said frames, a brace interconnecting said frames extending diagonally from one side of said top frame to said base frame, a member connected to a plurality of said springs and extending substantially parallel to said base frame, and a brace connected to and extending diagonally from the opposite side of said top frame and connected to said member.

4. In a spring seat, the combination of a base frame, a plurality of coil springs secured thereto, an upper frame comprising a border wire attached to certain of said springs, diagonal brace wires connecting said base frame and said border wire at one side of said seat, an anchoring wire secured to the lower portions of certain of said springs, and other diagonal brace wires connecting said anchoring wire and said border wire at the opposite side of said seat.

In testimony whereof, I affix my signature.
HENRY A. WAGNER.
